UNITED STATES PATENT OFFICE.

QUINCY A. GATES, OF WILKES-BARRE, PENNSYLVANIA.

JAR-CLOSURE.

1,341,897.

Specification of Letters Patent. Patented June 1, 1920.

Application filed February 14, 1919. Serial No. 277,065.

To all whom it may concern:

Be it known that I, QUINCY A. GATES, a citizen of the United States, residing at Wilkes-Barre, in the county of Luzerne and 5 State of Pennsylvania, have invented certain new and useful Improvements in Jar-Closures, of which the following is a specification.

This invention relates to jar closures, and 10 especially to fruit jar closures.

The object of the invention is to provide a simple and efficient closure of this character which, when secured, will be airtight without necessitating the use of a rubber gasket.

15 Another object of the invention is to provide a cover between which and the jar is provided a sealing groove to receive a sealing material which performs the double function of an auxiliary air excluder and an 20 indicator to show whether or not the contents remain intact.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:

Figure 1 represents a vertical section through the upper portion of a jar equipped 35 with this improved closure,

Fig. 2 is a horizontal section taken on the line 2—2 of Fig. 1, and

Fig. 3 is a detail sectional view showing a slightly different form of the invention.

40 In the embodiment illustrated in Figs. 1 and 2 a glass fruit jar 1 is shown having the usual upstanding neck 2. This neck 2 is provided at the mouth around the perimeter with segmental cutout portions 3 to receive 45 cam-shaped segmental sections 6 carried by the closure 5 as, will be hereinafter more fully described. This neck 2 also has annular segmental grooves 4 which are arranged in substantial horizontal alinement 50 with the bottom portions of the recesses 3 to receive the locking segments 6 when a partial turn is imparted to the cap-like closure 5.

The closure 5 has an annular outstanding 55 flange 7, the periphery of which is beveled

on its upper face as shown at 8 for a purpose to be described.

The jar 1 has the usual shoulder 9 between the neck 2 and the body portion and extending upwardly from the outer edge of 60 said shoulder is an annular flange 11 between which and the bevel-edge of flange 7 is formed a groove 12 to receive a sealing material shown at 13 which is preferably sealing wax or paraffin. This groove is 65 substantially V-shape in cross section so that when the sealing material is inserted an air-tight connection will be formed between the jar and its closure. This sealing material will indicate if there is any leakage since bubbles will appear at the surface thereof.

From the above description it will be obvious that the closure 5 may be readily applied to the jar by positioning it over the 75 mouth of neck 2, with the segments 6 arranged to register with the recesses 3, and when said cap is lowered with these segments extending into the recesses, and a partial turn imparted thereto, the segments 80 will pass into the grooves 4 in the jar neck and securely lock the closure to the jar. After the parts have been so assembled the sealing material is applied in the manner above set forth.

85 In the form shown in Fig. 3, the jar 1^a is constructed the same as jar 1 shown in the other figures with the upstanding annular flange 10^a, the neck 2^a thereof instead of having the recesses and undercut grooves, 90 is provided with the usual screw threads 5^b. The jar closure 5^a is also threaded in the usual manner, the flange 7^a thereof being beveled to form the V-shaped groove between it and flange 10^a to receive the sealing 95 material.

From the foregoing description, taken in connection with the accompanying drawings, the advantages of the construction and of the method of operation will be readily 100 apparent to those skilled in the art to which the invention appertains and while I have described the principle of operation of the invention together with the device which I now consider to be the best embodiment 105 thereof, I desire to have it understood that the device shown is merely illustrative and that such changes may be made as are within the scope of the claimed invention.

Having thus fully described my invention, 110

what I claim as new and desire to secure by Letters Patent, is:—

The combination of a jar having an upstanding neck with segmental cutout portions in its mouth around the perimeter thereof, said neck also having peripherally disposed grooves on its inner face connecting said cutout portions below the outer edge of the neck and a cap like closure for 10 said jar with an annular outstanding flange on the edge thereof, the periphery of which is beveled on its upper face said closure also having locking segmental ribs on the inner face of the side walls thereof adapted

to register with the cutout portions of the 15 neck of the jar and to enter the grooves thereof when a partial turn is imparted to the closure, said jar having an upstanding flange forming a groove between it and the beveled edge of the closure to receive a sealing material.

In testimony whereof I affix my signature in presence of two witnesses.

QUINCY A. GATES.
